UNITED STATES PATENT OFFICE.

JOE SMITH AND FRANK M. FOX, OF SPRINGVILLE, NEW YORK.

WOODWORKING-MACHINE.

SPECIFICATION forming part of Letters Patent No. 641,159, dated January 9, 1900.

Application filed October 25, 1898. Serial No. 694,524. (No model.)

To all whom it may concern:

Be it known that we, JOE SMITH and FRANK M. FOX, citizens of the United States, residing at Springville, in the county of Erie and State 5 of New York, have invented certain new and useful Improvements in Woodworking-Machines, of which the following is a full and complete specification, such as will enable those skilled in the art to which it appertains 10 to make and use the same.

This invention relates to woodworking-machines; and the object thereof is to provide an improved attachment for use in connection with machines of this class, said attachment 15 consisting of a detachable head for use in connection with the spindles or mandrels of such machines, said detachable head being provided with devices adapted to serve as a plain cutter and joiner or as a matcher and joiner 20 and for cutting tongues and grooves in flooring and for other and similar purposes.

The invention is fully disclosed in the following specification, of which the accompanying drawings form a part, in which—

25 Figure 1 is an end view of a support or bench provided with a vertically-movable frame having a mandrel mounted therein, the upper end of which is provided with our improved matcher and joiner head; Fig. 2, a 30 sectional side view thereof; Fig. 3, a side view of the improved matcher and joiner head which we employ arranged for forming grooves; Fig. 4, a similar view of the same device arranged for forming tongues; Fig. 5, 35 a section of Fig. 4 on the line 5 5; Fig. 6, a side view of a screw-threaded hollow cylindrical sleeve which forms a part of the matcher and joiner head; Fig. 7, a bottom plan view of the device as shown in Fig. 3; Fig. 8, a top 40 plan view thereof; Fig. 9, a plan view of the base disk or cutter of the cutter and joiner head. Fig. 10 is a bottom plan view of an interchangeable top disk or cutter of the matcher and joiner head as shown in Fig. 3, 45 said disk or cutter being adapted for use in making grooves; and Fig. 11, a view similar to Fig. 5, showing a modified form of construction.

In the drawings forming part of this specification the separate parts of our improvement are designated by the same numerals of

reference in each of the views, and in said drawings we have shown in Fig. 2 a part of a bench 12, which is provided at one end with a stationary vertical frame 13, which is provided at each side with vertical slots 14, and we also employ a vertically-movable mandrel frame or support 15, which is connected with the vertical frame 13 by screws or bolts 16, which are passed through the slots 14 and 55 screwed firmly into the vertically-movable mandrel frame or support 15, and at the bottom of the stationary frame 13 is a bearing 17, through which passes a screw-threaded bolt 18, by means of which the vertically-movable 60 mandrel frame or support 15 may be adjusted vertically, as desired.

Mounted centrally and vertically in the mandrel frame or support 15 is a mandrel 19, provided centrally with a power pulley or 70 drum 20, and connected with the upper end of said mandrel 19, above the vertically-movable frame or support, is our improved matcher and joiner head 21.

The upper end of the mandrel 19 is screw-threaded, as shown at 22 in Fig. 5, and is provided with a nut 23, and mounted on the upper end of said mandrel and secured thereto by a screw 24 is a hollow cylindrical sleeve 25, which is provided adjacent to its lower end 80 with a screw-thread 26 and at the upper end with an oppositely-arranged screw-thread 27, and the improved matcher and joiner head which consists of a plurality of parts, as hereinafter described, is connected with said 85 sleeve.

In the construction of our improved combination matcher and joiner head we provide a collar 28, which is adapted to be secured to the lower end of the sleeve 25 and which is 90 provided with a tubular extension 29, which is similarly threaded, and we also employ a base cutter 30 and an interchangeable top cutter disk or plate 31, above which is placed a collar 32, which is provided with a thread 95 similar to the thread 27 on the upper end of the top sleeve 25.

The base cutter disk or plate 30 is circular in form, as shown in Fig. 9, said figure being a plan view thereof, and said cutter disk 100 or plate is provided on its upper side with two quadrant-shaped raised portions 33 of

less diameter than the disk or cutter, whereby two similar quadrant-shaped depressions 34 are formed, and at regular intervals in the perimeter of said cutter disk or plate 30 are formed cavities or recesses 35, whereby the cutting teeth or edges 36 are formed, all of which project in the same direction.

In practice the matcher and joiner head is revolved in the direction in which the cutter 10 teeth or edges 36 project, and the inner walls of the cavities or recesses 35 are preferably curved, as shown in Fig. 9.

The upper interchangeable cutter disk or plate 31 (shown in Fig. 10) is designed for use 15 in cutting grooves and is provided on its lower surface with two quadrantial raised portions 37, which are of greater diameter than the body portion of said disk or cutter and whereby two corresponding depressions 38 are 20 formed, and these parts correspond with the parts 33 and 34 of the base disk or cutter 30 and interlock therewith, and said disk or cutter is provided with notches or recesses 39 similar to the notches or recesses 35 in the 25 base disk or cutter 30, and whereby projecting cutting teeth or edges 40 are formed.

In the form of construction shown in Fig. 10 two of these cutting teeth or edges 40 are farther from the center of the disk or cutter 30 than the other two, and those which are nearer the center of the disk or cutter are designed for planing the bottom of the groove formed thereby. These parts in practice are connected as shown in Figs. 3 and 5, the base 35 disk or cutter 30 being mounted on the tubular extension 29 of the collar 28, as is also the top disk or cutter 31, and said parts are clamped together by the collar 32, and the top disk or cutter 31 is provided with screws or 40 bolts 41, any desired number of which may be employed, said screws or bolts being passed therethrough and adapted to bear on the upper side of the base disk or cutter 30, so as to increase or diminish the width of the groove 45 formed in the operation of the device.

By reason of the fact that the raised portions 37 on the bottom of the top disk or cutter 31 are radially wider than the body of said disk or cutter the said disk or cutter is provided with segmental sections 42, which project beyond the body thereof and in a lower plane, and the raised portions 33 on the upper surface of the bottom disk or cutter 30 are of less diameter than the body portion of 55 said disk or cutter.

The construction hereinbefore described is, as stated, designed particularly for forming grooves, and in forming the corresponding tongues we employ a top disk or cutter 43, a 60 side view of which is given in Fig. 4, and which is exactly of the shape and construction as the bottom disk or cutter 30, but preferably of slightly less diameter, and said disk or cutter 43 is provided on its underside with raised 65 portions which interlock with the raised portions 43 on the upper side of the bottom disk

or cutter 30, and the disk or cutter 43 is also provided with cutting teeth or edges 44, similar to the cutting teeth or edges 36 on the bottom disk or cutter, and with the screws or 70 bolts 41, which pass therethrough and by means of which the distance between the bottom disk or cutter 30 and the top disk or cutter 43 may be regulated. It will also be seen that the raised portions 33 on the upper side of the 75 bottom disk or cutter 30 are provided at one end with cutting teeth or edges 46, and in practice the corresponding parts of the top disk or cutter 43 are similarly provided. We have not shown the top disk or cutter 43 in detail by 80 reason of the fact that the construction on its under side is exactly the same as the construction of the bottom disk or cutter 30 on its upper side, and a detail illustration thereof is not, therefore, considered necessary. In Fig. 85 11 we have shown our improved matcher and joiner head, the details of which have been hereinbefore described, connected with an ordinary spindle, which takes the place of the mandrel heretofore described, and in this form 90 of construction we substitute for the cylindrical hollow sleeve 25 a solid cylindrical attachment 55, into the lower end of which the mandrel 19 passes, said parts being connected by the set-screw 24, and otherwise this 95 construction is similar to that hereinbefore described and clearly shown in Fig. 5. It will be apparent, however, that either of the forms of construction hereinbefore described may be used with the ordinary spindle or with a 100 vertically-movable mandrel and mandrel-frame, and the words "mandrel" and "spindles" as used herein may each be considered as referring either to a spindle or mandrel as used in machines of the class referred to. 105

Having fully described our invention, we claim as new and desire to secure by Letters Patent—

1. A mandrel provided with a sleeve 25 having oppositely-directed threads formed thereon, a collar mounted on said sleeve and provided with a tubular extension, a bottom disk or cutter 30 mounted on said tubular extension and an interchangeable top disk or cutter mounted thereon, and adapted to be 115 clamped to the bottom disk or cutter, said disks or cutters being provided on their adjacent sides with interlocking projections or raised portions and at their perimeters with cutting teeth or edges, substantially as shown 120 and described.

2. A mandrel provided with a cutter-head, consisting of a bottom disk or cutter, and interchangeable top disks or cutters, said bottom disk or cutter being provided on its upper side with raised portions, and said interchangeable top disks or cutters being provided on their lower sides with corresponding raised portions, said disks or cutters being provided at their perimeters with cutting 130 teeth or edges, and the raised portion on the bottom of one of the interchangeable disks or

cutters being wider than the body portion, and being provided with cutting teeth or edges, substantially as shown and described.

3. A mandrel provided with a cutter-head, 5 consisting of a bottom disk or cutter, and interchangeable top disks or cutters, said bottom disk or cutter being provided on its upper side with raised portions, and said interchangeable top disks or cutters being provided on their lower sides with corresponding raised portions, said disks or cutters being provided at their perimeters with cutting teeth or edges, and the raised portion on the bottom of one of the interchangeable disks or 15 cutters being wider than the body portion, and being provided with cutting teeth or edges, and means for adjusting the space between said disks or cutters and for clamping the same in position, substantially as shown 20 and described.

4. In a woodworking - machine, a vertically-adjustable mandrel-support, a mandrel mounted therein, a sleeve connected with said mandrel and provided with oppositely - directed screw - threads, a collar mounted on 25 said sleeve and provided with a tubular extension, a bottom disk or cutter mounted on said collar and interchangeable top disks or cutters adapted to be mounted on said extension and clamped in connection with said bottom disk or cutter, substantially as shown and 30 described.

5. In a woodworking - machine, a vertically-adjustable mandrel-support, a mandrel 35 mounted therein, a sleeve connected with said mandrel and provided with oppositely - directed screw-threads, a collar mounted on said sleeve and provided with a tubular extension, a bottom disk or cutter mounted on said collar and interchangeable top disks or cutters 40 adapted to be mounted on said extension and clamped in connection with said bottom disk or cutter, said bottom disk or cutter being provided on its upper side with raised portions, and said interchangeable disks or cutters being provided on their lower sides with corresponding raised portions, said disks or 45 cutters being provided at their perimeters with cutting teeth or edges, substantially as shown and described.

6. In a woodworking - machine, a vertically-adjustable mandrel-support, a mandrel 50 mounted therein, a sleeve connected with said mandrel and provided with oppositely - directed screw-threads, a collar mounted on said sleeve and provided with a tubular extension, a bottom disk or cutter mounted on said collar and interchangeable top disks or cutters 55 adapted to be mounted on said extension and clamped in connection with said bottom disk or cutter, said bottom disk or cutter being provided on its upper side with raised portions, and said interchangeable disks or cutters being provided on their lower sides with 60 corresponding raised portions, said disks or cutters being provided at their perimeters

with cutting teeth or edges, and means for adjusting the space between the bottom disk or cutter and the interchangeable disks or cutters, substantially as shown and described.

70

7. In a woodworking - machine, a vertically-adjustable mandrel-support, a mandrel mounted therein, a sleeve connected with said mandrel and provided with oppositely - directed screw-threads, a collar mounted on 75 said sleeve and provided with a tubular extension, a bottom disk or cutter mounted on said collar and interchangeable top disks or cutters adapted to be mounted on said extension and clamped in connection with said bottom disk or cutter, said bottom disk or cutter being provided on its upper side with raised portions, and said interchangeable disks or cutters being provided on their lower sides with corresponding raised portions, said disks or 80 cutters being provided at their perimeters with cutting teeth or edges, and means for adjusting the space between the bottom disk or cutter and the interchangeable disks or cutters, the raised portions on the bottom of one 85 of said interchangeable disks or cutters being of greater radial diameter than the body thereof and being provided with cutting teeth or edges, substantially as shown and described.

8. A woodworking-machine provided with 90 a vertically - adjustable frame, a mandrel mounted vertically therein, a screw-threaded sleeve secured to the upper end of said mandrel, a screw-threaded collar mounted on said sleeve and provided with a tubular extension, 95 a bottom disk or cutter mounted on said extension, an interchangeable top disk or cutter also mounted on said extension, said disks or cutters being adapted to interlock, and means for clamping disks or cutters together, 100 substantially as shown and described.

9. A woodworking device provided with 105 a vertically - adjustable frame, a mandrel mounted vertically in said frame, a screw-threaded sleeve secured to the upper end of said mandrel, a screw-threaded collar mounted on said sleeve and provided with a tubular extension, a bottom disk or cutter mounted on said extension, an interchangeable top disk or cutter also mounted on said tubular 110 extension, said disks or cutters being provided with interlocking portions on their adjacent surfaces, and means for clamping said disks or cutters together, and for regulating the distance between the same, substantially 115 as shown and described.

10. A woodworking device provided with 120 a vertically - adjustable frame, a mandrel mounted vertically in said frame, a screw-threaded sleeve secured to the upper end of 125 said mandrel, a screw-threaded collar mounted on said sleeve and provided with a tubular extension, a bottom disk or cutter mounted on said extension, an interchangeable top disk or cutter also mounted on said tubular 130 extension, said disks or cutters being provided with interlocking portions on their ad-

jacent surfaces, and means for clamping said disks or cutters together, and for regulating the distance between the same, consisting of screws passed through the upper disk or cutter and adapted to bear on the bottom disk or cutter, substantially as shown and described.

In testimony that we claim the foregoing

as our invention we have signed our names, in presence of the subscribing witnesses, this 21st day of October, 1898.

JOE SMITH.

FRANK M. FOX.
